(57) **CLAIM**

The ornamental design for a video camera, as shown and described.

DESCRIPTION

FIG. 1 is a perspective view of a video camera showing our new design;

FIG. 2 is a perspective view thereof wherein the viewing screen is in an open position;

FIG. 3 is a front elevational view of the video camera of FIG. 1;

FIG. 4 is a rear elevational view thereof;

FIG. 5 is a right side elevational view thereof; and,

FIG. 6 is a top plan view thereof.

The broken line portions in all views are shown to illustrate environment only and form no part of the claimed design.
